CIRCULAR SLIDE WIRE RESISTANCE ELEMENT

Edward A. Hamacher, Irvington, and Kurt Lowitzsch, Yonkers, N. Y., assignors to Philips Laboratories, Inc., Irvington-on-Hudson, N. Y.

Application November 22, 1952, Serial No. 322,018

6 Claims. (Cl. 201—56)

1

This invention relates to an improved contact brush construction and assembly for a circular or helical slide wire resistance element, and more particularly for the measurement of the resistance between the end of the resistance element and the brush contact when the brush contact is stationary.

Heretofore, the contact brush utilized in a resistance element was continually in engagement with the resistance element and since the contact traversed the resistance element a great number of times in the course of its use, the resistance element showed excessive and rapid wear resulting in change in resistance values.

A primary object of the present invention is to provide a contact brush construction and assembly which is adapted to be normally disengaged from the resistance element winding yet which may effectively and rapidly be placed into engagement with the resistance element winding when the proper resistance setting on the resistance element winding is determined. It is apparent, therefore, that since there is only intermittent contact of the contact brush with the resistance element winding, the wear on the winding is considerably reduced necessitating less frequent replacement thereof.

Another object is to provide a rugged and compact helical slide wire contact brush construction and assembly which will operate in a reliable and efficient manner.

The above and other features, objects and advantages of the present invention will be fully understood from the following description considered in connection with the accompanying illustrative drawings, in which is shown a perspective view, partially cut away, of the device embodying the present invention.

Referring more particularly to the drawing, the helical slide wire 2 is secured to the inner wall of cylinder 4. The cylinder is preferably formed from Bakelite or from some other suitable plastic composition. A main drive shaft 6 projects through cylinder 4 and is positioned coaxially to said cylinder. Main drive shaft 6 rotates in either direction by means of a motor coupled thereto (not shown). A sleeve 8 surrounds, and rotates freely about the main drive shaft 6, and at both ends is provided with a pair of flat members 10 connected together by a tie rod 12. Another pair of relatively flat elements 14 are fixed to main drive shaft 6 adjacent to flat members 10. A spacer rod 16 is secured at both its ends to elements 14. It is to be noted that since spacer rod 16 is secured to main drive

2

shaft 6, the spacer rod always maintains the same relative position with respect to the main drive shaft.

5 A contact brush holder 18 composed of insulating material is provided in its upper portion with an aperture 20 therethrough and two upright guide parts 22. A contact brush 24 is secured between parts 22 and is adapted to engage helical slide wire 2 in a predetermined position of holder 18. Contact brush holder 18 is adapted to ride on and traverse spacer rod 16 since the spacer rod projects through the aperture 20 of holder 18. The lower portion of holder 18 has a recess 28 which has tie rod 12 positioned therein thereby providing a track for contact brush holder 18 to traverse thereon. A shaft 28 is mounted in drive shaft 6 and has secured to it a transverse pin 30. Pin 30 protrudes through a slot 32 in main drive shaft 6, said slot being positioned 10 parallel to the longitudinal axis of the main drive shaft, and a slot 34 cut in sleeve 8 and inclined to the axis of the sleeve.

15 The operation of the device is as follows: Main drive shaft 6, in this instance, rotates in a clockwise direction and is adapted to be stopped in order to take a resistance reading. The contact brush 24 may be moved manually or mechanically into engagement with helical slide wire 2 by merely moving shaft 28 in the direction of arrow 23 A. This causes transverse pin 30 to move in slot 32 in a direction parallel to the longitudinal axis of main drive shaft 6. Simultaneously the pin 30 engages inclined slot 34. Due to the angle of the slot, sleeve 8 and tie rod 12 rotate in a clockwise direction as indicated by arrow C, thus enabling tie rod 12 to pivot brush holder 18 on spacer rod 16 in a counter-clockwise direction as indicated by arrow D. This slight rotation of brush holder 18 enables the contact brush to engage slide wire 2. It is to be noted that insulated guide parts 22 are located between adjacent windings of the slide wire. It is also apparent that the brush holder is carried along the tie rod 12 and the spacer rod 16 in a direction parallel to the longitudinal axis of cylinder 4 upon rotation of sleeve 8. In addition, brush holder 18 may be rotated about spacer rod 16 so that the contact brush 24 may disengage the helical slide wire. Brush holder 18 is free to rotate about spacer rod 16 when shaft 28 is moved in the direction of arrow B thereby causing transverse pin 30 to move in slot 32 thereby engaging inclined slot 34 causing sleeve 8 to rotate in a counter-clockwise direction, thus permitting tie rod 12 to move 20 in a counter-clockwise direction in the recess 28

of brush holder 18 thereby moving contact brush 24 out of engagement with slide wire 2, with a small clearance. The above method of engaging the contact brush and the slide wire by rotating the contact brush holder has the advantage of causing a slight wiping or self-cleaning action in order that good contact between the contact brush and slide wire is assured. This wiping action will not cause excessive wear since the contact brush seldom comes to rest at exactly the same point on the slide wire.

The present device has been used in conjunction with an analogue computer of the type in which a helical slide wire is driven by means of a motor and is automatically recycled in such a manner that if the contact brush was in continual engagement with the resistance element, the wear, especially at one end thereof would be extremely high. It is to be understood that we do not wish to be limited to a construction wherein the present device is used with a computer of the type stated above, but to any structure where a variable circular slide wire resistance may be used effectively.

While we have shown and described the preferred embodiment of our invention, it will be understood that the latter may be embodied otherwise than as herein specifically illustrated or described and that in the illustrated embodiment certain changes in the details of construction and in the arrangement of parts may be made without departing from the underlying idea or principle of the invention within the scope of the appended claims.

What we claim is:

1. A helical slide wire resistance element comprising a main drive shaft, a sleeve rotatable about said drive shaft, a pivoting brush contact holder being provided with a brush contact which is adapted to contact said wire resistance element when said sleeve operatively engages said brush contact holder upon rotation of said sleeve in a predetermined direction and rod means within said main drive shaft for coacting with said sleeve to enable said brush contact to engage and disengage said wire resistance element.

2. A helical slide wire resistance element comprising a main drive shaft, a sleeve rotatable about said drive shaft, a pivoting brush contact holder being provided with a brush contact which is adapted to engage said wire resistance element when said sleeve is rotated in one direction and disengage said wire resistance element when said sleeve is rotated in an opposite direction, and rod means in said main drive shaft for coacting with said sleeve to enable said brush contact to engage and disengage said wire resistance element.

3. A helical slide wire resistance element comprising a main drive shaft, a sleeve rotatable about said drive shaft, a pivoting brush contact holder being provided with a pair of spaced guide members, an arcuate brush contact positioned

between said guide members and being adapted to contact said wire resistance element when said sleeve operatively engages said brush contact holder upon rotation of said sleeve in a predetermined direction and rod means within said main drive shaft for coacting with said sleeve to enable said brush contact to engage and disengage said wire resistance element.

4. A helical slide wire resistance element comprising a main drive shaft, a sleeve rotatable about said drive shaft, a pivoting brush contact holder being provided with a brush contact which is adapted to contact said wire resistance element when said sleeve operatively engages said brush contact holder upon rotation of said sleeve in a predetermined direction and rod means within said main drive shaft being provided with a pin positioned substantially perpendicular to said rod means and adapted to coact with said sleeve to rotate said sleeve in one direction thereby causing an engagement of said brush contact with said slide wire resistance element and in another direction thereby causing a disengagement of said brush contact with said slide wire resistance element.

5. A helical slide wire resistance element comprising a main drive shaft, a sleeve rotatable about said drive shaft, first rod means, means securing said first rod means to said sleeve, a pivoting brush contact holder, means pivotally securing said brush contact holder to said main drive shaft, a brush contact attached to said brush contact holder which is adapted to contact said wire resistance element when said first rod means engages said brush contact holder upon rotation of said sleeve in a predetermined direction, and second rod means within said main drive shaft for coacting with said sleeve to enable said brush contact to engage and disengage said wire resistance element.

6. A helical slide wire resistance element comprising a main drive shaft, a sleeve rotatable about said main drive shaft, first rod means, means securing said first rod means parallel to said sleeve and rotatable therewith, second rod means, means securing said second rod means to said main drive shaft and parallel thereto, a brush contact holder pivoting on said second rod means, a brush contact attached to said brush contact holder which is adapted to contact said wire resistance element when said first rod means engages said brush contact holder upon rotation of said sleeve in a predetermined direction, and third control rod means within said main drive shaft movable co-axially with said main drive shaft and for coacting with said sleeve to enable said brush contact to engage and disengage said wire resistance element.
